UNITED STATES PATENT OFFICE.

IRA M. THURLOW, OF BELOIT, WISCONSIN, ASSIGNOR TO THE BERLIN MACHINE WORKS, OF BELOIT, WISCONSIN, A CORPORATION OF WISCONSIN.

SELF-CENTERING AND GAGE-SAWING DEVICE.

1,171,156.

Specification of Letters Patent.

Patented Feb. 8, 1916.

Application filed June 14, 1915. Serial No. 34,085.

To all whom it may concern:

Be it known that I, IRA M. THURLOW, a citizen of the United States, residing at Beloit, in the county of Rock and State of Wisconsin, have invented certain new and useful Improvements in Self-Centering and Gage-Sawing Devices, of which the following is a specification.

A band resaw is ordinarily supplied with four power driven feed rolls positioned in pairs on each side of the saw. In operation one pair is made rigid for gage sawing to produce a fixed thickness between the rigid rolls and the saw, the unevenness of the stock being taken care of by the other set of rolls which are ordinarily yielding. At other times it is desired to divide the unevenness of the stock and by linking both sets of rolls together cause them to move to positions equidistant from the saw line. This is called self centering.

The object of this invention is to accomplish either gage sawing or self centering in a convenient and practicable manner.

In order that the invention may be readily understood a preferred embodiment of the same is set forth in the accompanying drawing and in the description based thereon. As, however, the invention is susceptible of embodiment in other constructional forms the drawing and description are to be taken in an illustrative and not in an unnecessarily limiting sense.

In the drawing—Figure 1 is a side elevation of so much of a band re-saw as will serve to illustrate the invention; Fig. 2 is a top plan view partly in section; Fig. 3 is an end view; and Fig. 4 is a detail sectional view on the line 4—4 of Fig. 2.

The ordinarily rigid pair of feed rolls is indicated at 11—11, and the yielding or adjustable feed rolls at 12—12, mounted respectively upon the carriages 13 and 14 to slide upon the machine frame indicated generally at 15.

A pin 16 extending upwardly from its seat in the machine frame 15 serves as a pivot upon which swing two arms 17 and 18, the former having its free end connected by means of the screw 19 with the yielding feed roll carriage at 20, and being also connected by the link 21 with one end of a rocking lever 22, the opposite end of which is connected with the rod 23 controlled by double acting springs 24, 25, mounted upon

said rod between a central guiding abutment 26 and the collars 27 and 28, a nut 29 being provided for the adjustment of the tension of the springs. The end of the screw 19 is squared at 19^a in order to adjust the connection between the arm 17 and the feed roll carriage. The arm 18, likewise pivotally mounted upon the pin 16, is connected by means of the screw spindle 30 at 31 with the fixed feed roll carriage 13. The spindle 30 has also a squared end 30^a for purposes of adjustment.

The arm 18 of the fixed feed roll carriage has, in line with its pivotal mounting upon the pin 16, a pair of laterally extending ears 32, 32, upon which by means of the pivots 33 are fulcrumed the members 34, 34, of a pair of clamping levers each provided equidistant from its fulcrum with jaws 35, 36, the jaws 35 adapted to engage on the two side faces of the arm 17 and the jaws 36 adapted to engage the two side faces of the machine frame 15. The extreme upper ends of the levers are connected by means of a screw spindle 37 controlled by the hand wheel 38.

The operation is as follows: Where it is desired to do gage sawing the fixed feed rolls 11 are adjusted by means of the screw spindle 30 and the hand wheel 38 is turned to spread apart the upper ends of the clamping levers 34 whereby the jaws 36 are caused to securely engage the machine frame and the arm 18 is thus locked rigidly to the machine frame so as to prevent any movement of the arm upon its pivot 16. It will be seen that under these circumstances the feed rolls 11 are rigidly held while the feed rolls 12, having been adjusted by means of the screw spindle 19, will yield slightly under the control of the springs 24, 25. If it is desired to self center the rolls they will be brought by means of the screw spindles 19 and 30 to a position equidistant from the saw line or into such relation as the conditions of the work may require, whereupon the hand wheel 38 will be turned in such manner as to draw the upper ends of the lever 34 together releasing the jaws 36 from the machine frame and causing the jaws 35 to firmly grasp the arm 17. It will be seen that the two arms are now free to move independently of the machine frame, but are rigidly coupled together and left free to swing as an integral two-armed rocking

lever about the pivot 16 as a center and subject only to the yielding resistance of the double acting springs 24, 25.

I claim:

5. 1. In a resaw, the combination with two sets of feed rolls arranged one on each side of the saw, of two arms extending in a common plane, a connection between each of the arms and one of the sets of feed rolls, one of the arms free to move and the other yieldingly supported, a pair of clamping levers suitably fulcrumed and embracing one of the arms at one side of their fulcrum and embracing a portion of the machine frame at the other side of the fulcrum, and adjustable means connecting the clamping levers whereby to alternatively anchor one of the arms leaving the other free and to couple the two arms together to move in unison in opposite directions.
10. 2. In a resaw, the combination with two sets of feed rolls arranged one on each side of the saw, of two arms extending in a common plane, a connection between each of the arms and one of the sets of feed rolls, one of the arms free to move and the other yieldingly supported, a pair of clamping levers fulcrumed to one of the arms and embracing the other arm at one side of their fulcrum and embracing a portion of the machine
15. frame at the other side of the fulcrum, and adjustable means connecting the clamping levers whereby to alternatively anchor one of the arms leaving the other free and to couple the two arms together to move in unison in opposite directions.
20. 3. In a resaw, the combination with two sets of feed rolls arranged one on each side of the saw, of two arms oppositely extending from a common pivot, a connection between each of the arms and one of the sets of feed rolls, one of the arms free to move and the other yieldingly supported, a pair of clamping levers fulcrumed to one of the arms and embracing the other arm at one side of their fulcrum and embracing a portion of the machine frame at the other side of the fulcrum, a screw spindle connecting the clamping levers, whereby to alternatively anchor one of the arms leaving the other free and to couple the two arms together to move in unison in opposite directions.

frame at the other side of the fulcrum, and adjustable means connecting the clamping levers whereby to alternatively anchor one of the arms leaving the other free and to couple the two arms together to move in unison in 35 opposite directions.

3. In a resaw, the combination with two sets of feed rolls arranged one on each side of the saw, of two arms oppositely extending from a common pivot, a connection between each of the arms and one of the sets of feed rolls, one of the arms free to move and the other yieldingly supported, a pair of clamping levers fulcrumed to one of the arms and embracing the other arm at one side of their fulcrum and embracing a portion of the machine frame at the other side of the fulcrum, a screw spindle connecting the clamping levers, whereby to alternatively anchor one of the arms leaving the other free and to couple the two arms together to move in unison in 40 opposite directions.

In witness whereof I have hereunto signed my name in the presence of two subscribing witnesses.

IRA M. THURLOW.
